UNITED STATES PATENT OFFICE.

NIELS GEORG SÖRENSEN, OF STOCKHOLM, SWEDEN.

LOCK OR LATCH.

SPECIFICATION forming part of Letters Patent No. 425,707, dated April 15, 1890.

Application filed July 20, 1889. Serial No. 318,151. (Model.)

To all whom it may concern:

Be it known that I, NIELS GEORG SÖRENSEN, a subject of the King of Sweden, and a resident of Stockholm, Sweden, have invented 5 certain Improvements in Locks or Latches, of which the following is a specification.

My invention relates to locks or latches, and especially to such locks or latches as have gravity-bolts; and the principal object 10 of my invention is to provide means for retaining the bolt in its locking position in its eye or socket in whatever position the article to which the lock is applied may be placed, thus preventing unauthorized persons from 15 withdrawing the bolt by inverting or shifting the position of the article, or by similar methods.

My invention comprises, also, other features, that will be hereinafter described.

20 In the accompanying drawings I have shown my improvements embodied in several forms of locks and latches.

Figure 1 is a vertical section through the casing of a mortise-lock embodying my improvements; and Fig. 2 is a transverse section of the lock, taken on the line xx in Fig. 1. Figs. 3, 4, 5, and 6 illustrate another embodiment of my invention in a lock. Fig. 3 is a vertical section through the lock-casing; Fig. 4, a 25 horizontal section on line yy in Fig. 3; Fig. 5, a horizontal section on line $y'y'$ in Fig. 3, and Fig. 6 is a front elevation. This lock is adapted for use on drawers and the like. Figs. 7 and 8 illustrate the application of my 30 improved lock to the tail-board of a vehicle, Fig. 7 being a sectional elevation, and Fig. 8 a front elevation, of that portion of the vehicle on which the lock is mounted. Figs. 9 and 10 illustrate the application of my lock 35 to sliding doors, Fig. 9 being a front elevation of the doors, and Fig. 10 a horizontal section on line zz in Fig. 9. Figs. 11, 12, 13, and 14 illustrate my improved, adjustable eye or socket, Fig. 11 being a side elevation, partly 40 in section, and Fig. 12 a front view. Figs. 13 and 14 show the washer or distance-piece detached.

Referring to Figs. 1 and 2, A is the lock-casing. B is a portion of the part in which 45 the lock is mounted. C is a portion of the jamb or door-post. D is the eye or socket which receives the bolt of the lock, and E

is the key for operating the lock. a is the bolt, which is arranged to slide freely up and down in a compartment b in the casing A. c 55 c' are apertures provided in the wall of the compartment b . d is a slot formed in the bolt a . Through the aperture c and into the slot d extends the free extremity of a lever e , firmly attached to or forming a part of a boss 60 f , into a square or other suitably-formed hole or recess in which fits the spindle of the handle or handles. The extremity of the lever e forms the point of support for the bolt a . h is a weight pivoted at h' to 65 the casing A and arranged to bear against a projection upon the lever e in such a manner that the said lever e will be normally retained in its lowest position—that is to say, that position in which the bolt and the handle 70 or handles on the said spindle g are in the locking position. A suitable stop or stops is in some instances provided for limiting the downward movement of the lever e . When the door is open, the bolt a is in its lowest 75 position, and the lower end of said bolt is beveled or cut away, so that when the door is closed the bolt, by reason of the wedge-like action of the beveled portion, will be raised so as to pass over the edge of the eye or socket 80 D, which is in the path of the bolt a , and to drop into the recess in said socket. i are tumblers, which are pivoted at i' to the casing A. The tumblers i are provided with arms or extensions i^2 , which, when the said tumblers are not held up by the key, as herein-after described, extend through the aperture c' in the casing A, so that when the door is closed they will engage with a notch d' in the bolt a . i^3 are projections upon the extremities of the arms or extensions i^2 , intended to prevent the latter from engaging too deeply in said notch d' . It will be seen that it is impossible to lift the bolt a without previously disengaging the arms or extensions i^2 95 of the tumblers i from the notch d' . j is a stop for limiting the extent of the turning movement of the key E and the play of the tumblers i so as to render it impossible, under any circumstances, to introduce the key E. 100 By turning the key so as to raise the tumblers i the latter can be disengaged and the bolt a becomes free. Suitable wards or guards may be provided on the tumblers i and in the cas-

ing A for the further protection of the lock from being opened by unauthorized persons. Any suitable number of tumblers i may be employed, as, for instance, a group of levers 5 or tumblers arranged one behind the other, similarly to the levers or tumblers in a "Chubb's lock," and which can only be moved through the medium of a special key, so that they will liberate the bolt a .

10 The lock illustrated in Figs. 3 to 6 is designed more especially for a drawer, box, or the like. In this instance I make suitable provision for preventing the opening of the lock by inverting or turning upside down the 15 article to which it is attached. $k k'$ are suitable catches pivoted at k^2 to the casing A. The said catches $k k'$ are combined with stops l , which limit their movement and normally retain them in such a position that the bolt 20 a can be freely raised through the medium of the key E. Should the lock be turned upside down, the catches $k k'$ will turn about their pivots by reason of their weight and assume the position indicated by the dotted 25 lines, Fig. 3, thus entering the path of the bolt a and preventing the latter from falling back even should the tumbler i be liberated or disengaged from the bolt a on the lock being inverted. $m m$ are the other stops for 30 limiting the movement of the side-catches $k k'$ when displaced in the manner above described. The slot or recess d in the bolt a serves in this case for the engagement of the tumbler i , (one tumbler only being employed 35 in the arrangement shown,) and also for the insertion of the key E, by means of which the tumblers i may be first disengaged and the bolt a raised. I provide, moreover, for enabling the tumbler i , when 40 desired, to be fixed or retained in a position out of engagement with the bolt a . For this purpose I employ a pin n , which passes through a hole in the case A and the extremity of which is adapted to engage in a hole 45 n' , provided in the said tumbler in such a position that the latter will be retained out of engagement with the bolt a . o is another pin, the extremity of which also passes through a hole in the casing A, and is adapted to engage or enter a hole o' in the bolt a , thus 50 serving to fix or retain the bolt in its raised position, and permitting the drawer or other article to which the lock is attached to be opened and closed freely. The pins n and o extend through the key-plate o'' , and are provided with suitable knobs or handles by 55 means of which they may be operated from the exterior. The said pins can only be inserted in the hole n' in the tumbler or into the hole o' in the bolt a when the said bolt is raised by the tab of the key E.

Figs. 7 to 10 illustrate a modification of my improved lock adapted for use on trap and sliding doors for railway-carriages and the like. In the first arrangement shown in Figs. 65 7 and 8 the lock-casing A is attached to the

fixed frame p of the carriage, while the socket D is placed on the trap or door q , which is arranged to turn about its lower edge upon suitable hinges or joints q' . In a case in 70 which the door is arranged to turn upon its upper edge the lock is preferably placed upon the said trap or door while the eye or socket D is fitted into the frame p , or the said lock may be placed upon the said frame p above 75 the lower edge of the said trap or door. In the case of sliding doors q , as shown in Figs. 9 and 10, the lock A is secured in one of the said doors q , like a mortise-lock, or on the back of the said door, like a box or case lock, 80 or in the case of a sliding door having but one leaf, also in the frame of the door, while the said sliding door carries the eye or socket D.

In Figs. 11 to 14 I have shown the arrangement I prefer to employ for permitting any necessary adjustment of the eye or socket D in order to allow for shrinkage or warping of the doors or of the posts or jambs without in any way diminishing the security of the fastening of the eye or socket to the door frame or jamb. The eye or socket D, instead of being fastened directly to the door post or jamb C, as heretofore shown, is connected indirectly thereto through the medium of a plate 95 r , which is let into or countersunk in the said door post or jamb C, and secured thereto by means of two or more screws r' . In the plate r is provided a slot r^2 , of suitable length and width. $s s$ are screws which pass 100 through holes provided in the flange-plate D' of the eye or socket D and through the said slot r^2 in the plate r . The screws s are screwed into another plate t , placed behind the plate r , which plate t serves as a common 105 nut for both the screws s . A suitable recess C' is also provided in the door post or jamb C, adapted to receive the plate r and the extremities of the screws s . By means of this arrangement the eye or socket D and the 110 plate t can be displaced or adjusted in a vertical as well as in a horizontal direction, as far as the dimensions of the slot r^2 afford free play to the screws s . Thus, for example, the eye or socket D may be adjusted in a case 115 where a mistake has been made in the mounting of either the eye or socket D or the lock through incorrect measurement, and also in a case where the lower extremity of the bolt has been subjected to much wear and tear, or 120 the door has sunk or warped, or the relative positions of the door and its post or jamb have become altered from any cause, such as shrinkage or otherwise.

For cases in which the door has shrunk to 125 a considerable extent through the drying of the wood or from other causes, so that the bolt would drop against the edge of the eye or socket, instead of entering the hole or aperture in the latter, I provide washers or distance-pieces u , (seen in Figs. 13 and 14), having a slot or slots u' , so that they can be 130

passed over the shanks of the screws *s*. The said washers or distance-pieces *u* are made of different thickness, and one or more may be inserted between the flange-plate *D'* of the eye or socket *D* and the plate *r*, the screws *s* having first been slackened. The shape of the washers *u* is such as to correspond exactly to that of the flange *D'* of the socket *D*, and their front edges are beveled in the same manner as the front edge of the said eye or socket *D*. After the insertion of the requisite number of washers and the necessary vertical and horizontal adjustment has been made the screws *s* are firmly screwed down again into the plate *t*, so as to rigidly secure the socket *D* in position.

I have indicated in dotted lines in Fig. 11 the position that will be assumed by the washer *u*, although such washer is not actually shown in position in said figure. It is evident, moreover, that I may somewhat modify the construction and arrangement of my improved latch or lock without materially departing from the nature of my invention.

Having thus described my invention, I claim—

1. In a lock or latch, the combination, with a gravity-bolt and the lifter for the same, of one or more tumblers having arms which normally engage a locking-notch in the said bolt

when the latter is in its locking position, and a lifter for said tumbler or tumblers.

2. In a lock or latch, the combination, with a gravity-bolt and a lifter therefor, of one or more gravity-catches adapted to fall into the path of the bolt and prevent its withdrawal when the lock is inverted, substantially as set forth.

3. The adjustable eye or socket, consisting of a slotted plate adapted to be secured to the jamb or other part, a nut-plate under the said slotted plate, the socket proper having a flanged plate, and the screws which pass through the flanged plate of the socket and the slot in the fixed plate and screw into said nut-plate, all combined and arranged substantially as set forth.

4. The combination, with the adjustable eye or socket, of the slotted washer or distance-piece, said washer having open slots to engage the attaching-screws, and having the form and size of the flanged plate of the eye or socket.

In witness whereof I have hereunto signed my name in the presence of two subscribing witnesses.

NIELS GEORG SÖRENSEN.
